UNITED STATES PATENT OFFICE.

FLORENT HINNEKENS, OF PATERSON, NEW JERSEY.

FABRIC SPRAYER.

Application filed January 22, 1926. Serial No. 83,068.

This invention relates to apparatus for treating fabrics in the rope form with liquids, as phosphating liquid and water for washing, and in particular to the device for 5 supplying the liquid to the fabric. In phosphating and washing the fabric, in the form of a rope, extends around a succession of suitably rotated drums, each turn of the fabric around a drum hanging therefrom in 10 a loose bight into a vat or vat-section, and the liquid is supplied to the rope by a nozzle so shaped that the rope passes through it; thus there is produced a succession of liquid-treating units, and generally every other 15 nozzle supplies phosphate liquid and the remainder washing water. This system of course only illustrates one application of the present invention, which consists in part of a nozzle through which the rope may be 20 passed and which I have constructed so that it is interchangeably adapted for either a flooding delivery or a spraying delivery of the liquid and also so that while the body of the device is formed of metal provision is 25 made for protecting the goods from contact with such metal body.

In the drawing,

Fig. 1 is a vertical sectional view, showing a fragment of the rope and the parts in position for a flooding liquid-delivery;

Fig. 2 is a similar view, the rope being omitted and the parts in position for spraying; and

Fig. 3 is a plan.

The nozzle casing 1 is an annular structure having an inlet 2, to which the liquid supply pipe 3, having a regulating valve 3^a, may be suitably connected. It contains an annular upstanding wall concentric with its 40 annular or vertical wall and of sufficiently less diameter than the latter to divide the space within the casing into a passage proper formed in said annular wall and an annular chamber 4 surrounding the latter, said 45 upstanding wall being here formed by a sleeve 5 which is threaded at 5^a and screwed up into a threaded opening 1^a in the bottom wall of the casing. The sleeve may by turning it be made to stand at any desired elevation, thus being in effect a valve, and when 50 adjusted to that end it may be secured by a lock-nut 6 preferably packed, as at 6^a. The top of the casing is formed as a horizontal wall 1^b which is provided with a central 55 opening 7 of less diameter than sleeve 5; in other words 1^b forms an inward continuous

flange overhanging the sleeve all around. In applying certain liquids, as in washing, the rope A of goods should be deluged with the liquid, wherefore the sleeve is then adjusted down (Fig. 1); in applying other liquids, as in phosphating, a forceful jet or spray is wanted, wherefore the sleeve is then adjusted up (Fig. 2), leaving a more or less narrow continuous slit between its upper 60 edge and flange 1^b.

It is desired to provide for guiding the rope A clear of contact with the casing 1, which is of metal, so that by corrosion thereof due to chemicals in the liquids or 65 otherwise the goods will not be stained or in any way injured; it is also desired that the construction of the device should insure a deluging or flooding of the goods as complete as possible when the sleeve is set for 70 the flooding operation. To these ends I provide the upper ring 8 and the lower ring 9, these being preferably of some vitreous or other substance which will not stain or 75 otherwise injure the goods.

The ring 8 preferably has a smooth convex cross-section, and it is mounted loosely in a top housing of the casing formed by an upstanding concentric wall 1^c thereon; the ring 8 seats on the flange 1^b and loosely fits 80 in the housing.

Ring 9 preferably has an inwardly beveled top surface and its inner edge is convex or rounded in cross-section and its seats on an inward flange 5^b of sleeve 5; it is capable 85 of removal, but it more or less snugly fits the sleeve.

The purpose of spraying the goods is to obtain good penetration thereof by the spraying liquid (as phosphate liquor) without wasteful use of the liquid. When washing is done, however, it is important to supply the washing liquid in copious quantity, or in short to flood or deluge the goods. The goods in passing through the rings 8 90 and 9 fits them fairly closely (though not so closely when used in the phosphating and washing system mentioned in the opening part of this specification but that it will fall of its own weight therethrough) and 100 this traps the liquid in the zone of ring 9 so that even when the device is used as a spray there is a flooding of the goods in the zone above ring 9 and around the goods and the escape of the liquid from the nozzle is almost 105 entirely as an incident of absorption, wherefore complete saturation is a necessary result 110

and little of the liquid leaves the nozzle without doing service, which in the case of the phosphating liquor means an appreciable economy. The method here indicated is I believe is in itself new in the art; wherefore I claim it herein.

It is preferable to coat all metal parts with porcelain or other vitreous substance in order to protect the goods from any possibility of their being stained by corrosive deposits present on the parts.

Having fully described my invention what I claim and desire to secure by Letters Patent is:

- 15 1. A nozzle of the class described including, with a casing having an aperture therethrough through which the goods to be treated extends and a liquid space arranged to flank and being open toward the goods when extending through said aperture, a valve movable in the casing back and forth lengthwise of the direction in which the goods extends to vary the liquid flow from said space, said nozzle having means to admit liquid to said space.
- 20 2. A nozzle of the class described including, with a casing having an aperture therethrough through which the goods to be treated extends and a liquid space formed to surround and being open inwardly toward the goods when extending through said aperture, an annular valve arranged to surround the goods when so extending through the aperture and movable in the casing back and forth lengthwise of the direction in which the goods extends to vary the flow from said space, said nozzle having means to admit liquid to said space.
- 25 3. A nozzle of the class described including a hollow casing having opposite spaced walls apertured for the reception of the goods to be treated and an annular wall in the casing arranged to extend around the goods and forming around itself within said casing an annular liquid chamber and being movable in one of said spaced walls toward and from the other, said nozzle having means to admit liquid to said chamber.
- 30 4. A nozzle of the class described including a hollow casing having opposite spaced walls apertured for the reception of the goods to be treated and an annular wall in the casing arranged to extend around the

goods and forming around itself within said casing an annular liquid chamber, said annular wall being screwed into one of the first-named walls and forming with the other wall a liquid outlet from said space, and said nozzle having means to admit liquid to said space.

5. A nozzle of the class described including a hollow casing having opposite spaced walls apertured for the reception of the goods to be treated and an annular wall in the casing arranged to extend around the goods and forming around itself within said casing an annular liquid chamber and being screwed into one of said spaced walls and thereby movable therein toward and from the other, said nozzle having means to admit liquid to said chamber.

6. A nozzle of the class described including a hollow casing having opposite spaced upper and lower walls apertured for the reception of the goods to be treated, an annular wall in the casing arranged to extend around the goods and forming around itself within said casing an annular liquid chamber and being removably arranged in one of said spaced walls and spaced from the other, said nozzle having means to admit liquid to said chamber, and a goods-contact ring arranged to be penetrated by the goods and seated within the annular wall.

7. A passaged nozzle of the class described including two separable apertured parts arranged one within the other so that their apertures form longitudinally offset portions of a passage for the fabric to be treated, there being a liquid space around the passage and between said parts, said space having means to admit liquid thereto and means permitting liquid flow into the passage.

8. A passaged nozzle of the class described including two separable apertured parts arranged one within the other so that their apertures form longitudinally offset portions of a passage for the fabric to be treated, there being a liquid space around the passage and between said parts, said space having means to admit liquid thereto and said parts forming between them a liquid outlet from said space to said passage.

In testimony whereof I affix my signature.

FLORENT HINNEKENS.
